UNITED STATES PATENT OFFICE.

GEORGE W. TAFT, OF ABINGTON, CONNECTICUT.

MACHINE FOR MAKING, REPAIRING, AND CLEANING ROADS.

SPECIFICATION forming part of Letters Patent No. 333,572, dated January 5, 1886.

Application filed June 1, 1885. Serial No. 167,213. (No model.)

To all whom it may concern:

Be it known that I, GEORGE W. TAFT, a citizen of the United States, residing at Abington, in the town of Pomfret, in the county of Windham and State of Connecticut, have 5 invented certain new and useful Improvements in Machines for Making, Repairing, and Clearing Roads; and I declare the following to be a description of my said invention, sufficiently 10 full, clear, and exact to enable others skilled in the art to which it appertains to make and use the same, reference being had to the accompanying drawings, which form a part of this specification.

My present invention relates to that class 15 of road-machines in which the scraper mechanism is mounted in connection with a body or carrying frame supported by front and rear axles and traveling-wheels, and adapted 20 for oblique or diagonal adjustment in relation to the line of draft.

The objects of my present improvements 25 are to provide in a road-machine a diagonally-reversible scraper bar or blade having push-bars in rear thereof for sustaining the strain on the ends of said blade from the rear axle or back part of the carriage and capable 30 of ready adjustment; also to provide means for adjustably connecting said push-bars in a manner that will permit of their release 35 to accommodate the reversal or adjustment of the scraper to its several working positions; also to provide means for the convenient locking and unlocking of the push-bar-holding mechanism at the pleasure of the operator 40 from his position on the machine; also to provide in combination with the carriage and diagonally-reversible scraper-blade sustained by pushing-supports at the rear thereof, a 45 turn-table, pivot-beam, or swing-frame from which the blade is suspended; also to provide a hand-wheel and gear mechanism, in connection with said swing-frame, for effecting vertical adjustment of the blade or scraper and its push-frame independently at either end 50 thereof; also to provide an improved hand-wheel and gear-segment operating mechanism for manipulating and adjusting scrapers or blades in road-machines; also to provide means for conveniently stopping, holding, and releasing the lifting mechanism, and, generally,

to perfect and improve various details of construction and operation in machines of this class, as hereinafter more fully explained. These objects I attain by mechanism the 55 nature, construction, and operation of which are illustrated in the drawings, and explained in the following description, the particular subject-matter claimed being hereinafter definitely specified.

In the drawings, Figure 1 is a plan view of a road-machine embracing the features of my invention. Fig. 2 is a side view of the same, the rear corner being in section the better to show construction of under parts. Fig. 3 is 65 a transverse vertical section in rear of the scraper looking toward the front of the machine. Fig. 4 is a sectional plan view of the rear axle, push-bars, blade, and blade swinging appliances. Fig. 5 is a view similar to 70 Fig. 3, but showing some modification in the brake device, and in manner of attaching the elevating-bars, push-bars, and chains with the blade. Fig. 6 is a plan view of the swing-frame and brake-bar as shown in Fig. 5, and 75 Fig. 7 is side view showing a modification in manner of detachably securing the push-bars at the axle or rear part of the carriage.

In referring to parts, A denotes the carriage, body, or frame, B and B' indicate the traveling-wheels, and E E' the axles on which said body is mounted. The forward axle, E', is provided with suitable tongue and draft appliances, E², for the attachment of the team for drawing the machine in the usual manner. 80 The rear ends of the carriage-timbers are connected with the rear axle, E, by suitable castings and bolts at a. The axle E is in the present instance made as a round shaft, and is rigidly held in the frame-supporting castings. 85 The V-shaped thrust-frame C is provided with bearings or eye-castings that fit over the axle-shaft, so as to allow said frame to swing thereon as the blade is raised and lowered. If other form of axle is desired, the rear ends of the 90 thrust-frame C may be attached by any suitable hinge-connection, or as shown in my former Letters Patent No. 276,093. The scraper or blade D is preferably a curved steel plate, with a removable re-enforce on its working edge, although a scraper of any suitable 95 shape may be used, and, if desired, the scraper 100

may be furnished with a plow-point or with an adjustable wing-plate, or both, as shown in my former Letters Patent No. 315,184. This scraper-blade D is connected at its central lower part to the forward end of the thrust-frame C by a pivot-joint, d, that gives free movement for the diagonal and inclined adjustment of the blade. The hinging for backward and forward pitch of the blade may be on the same joint-piece or adjacent thereto. As a pivot-joint device for the attachment of the blade and thrust-frame in a road-machine is shown, described, and claimed by me in a separate application for Letters Patent, (see Serial No. 173,968,) it need not be more particularly herein described.

F F indicate adjustable push-bars, the forward ends of which are hinged or universally jointed to the rear lower part of the blade D, at or near the ends thereof, as indicated at d'. Said push-bars extend backward beneath the rear end of the machine, and are suitably supported by anti-frictional bearers at e, so as to slide longitudinally forward or back as the blade is reversed or swung horizontally to different positions of adjustment, and suitable means are provided at the junction of said push-bars with the carriage or its axle E for locking or detachably fastening said push-bars at their various positions of adjustment, so that they will sustain the rearward strain on the blade when the machine is at work.

In the present instance the locking devices consist of latch dogs or pawls I, pivoted on the axle E in a manner to swing up and down, and engaging with lugs or notches f formed on the bars F F at positions corresponding with the several adjustments required for the blade at either right or left diagonal and at a central position or squarely across the machine.

Combined with the dogs I or push-bar-locking mechanism I arrange devices whereby the operator from his position on the machine or platform A' can at will effect the release of the bars F F to permit the reversal adjustment of the blade D from one position to another, as may be desired. This releasing mechanism may be made, as indicated, with levers J, fulcrumed on the carriage-frame or under side of the platform, and connected at one end with the dogs I, and at the other with a foot-pedal, K, by depressing which the dogs will be disengaged from the bars F. Suitable springs, s, may be employed for pressing down the levers or dogs to prevent them from jarring out of place when the machine is at work.

Upon the carriage or body frame A there is arranged a turn-table or swing-frame, G, the ends or arms G' of which extend outward above the respective arms of the blade D, and the ends of said blade D are respectively suspended from adjusting mechanism mounted on said swing-frame and arranged for independently lifting or depressing either end of the scraper.

H H indicate the suspending rods or bars for supporting and adjusting the blade verti-

cally. Said bars are arranged to work up and down through suitable guides at or near the ends of the swing-frame G, their lower ends being linked to the blade D, as at h, or in other suitable manner, so as to give a flexible joint, while their upper portions are provided with connecting gears or racks h', that engage with pinions or lifting-wheels L, supported by short shafts or journal-studs l in suitable bearings, m, above the swing-frame G. Anti-friction rolls may be arranged at the back of the rack-bars H, for guiding and supporting them in contact with the pinions L. Rigidly connected with each of said pinions or lifting-wheels L, and turning on the same axis, is a large gear-segment, M, the peripheral circle of which is adapted for engagement with a small gear or pinion, N', that is connected with and is operated by a hand-wheel, N, arranged as indicated. The gears N' and hand-wheels N are connected to each other, or are fixed to the respective ends of short shafts or bearing-studs mounted to turn in bearing on the standards n, which latter are fixed upon the swing-frame G. Said standards support the mechanism at a position where the rims of the hand-wheels will be at a height convenient for the hand of the operator. The hand-wheel and gears are in the present instance arranged to work in planes parallel with the length of the swing-frame G, one set toward the right and the other toward the left, so as to bring the hand-wheel rims at the back of the turn-table or swing-frame and convenient for the operator standing on the platform A'.

At the rear edge of the swing-frame G stops or brake devices P are arranged for engaging the hand-wheels N for locking or holding the mechanism in position. Said brakes may consist of a pad, bearing-piece, or latch-dog b, connected with a rocking shaft, P', journaled in bearings on the beam G, and provided with a torsional or coiled spring, P'', for pressing the dog or pad against the rim of the wheel. A suitable pedal is provided in connection with the brake or stop, to enable the operator to throw off the brake and release the mechanism by pressure thereon with his foot.

As a modification, the brake device may be made as a long bar or flat spring extending from one wheel N to the other, and centrally supported by three studs projecting from the beam G in a manner to cause the ends to press up against the rims of the wheels N, the brake being released by pressing down the end thereof with the foot. The suspending-bars or racks are in the present instance located so as to mesh with the inner side of the pinions L, or at the same side of the axis as the segments; but, if desired, they might be arranged at the opposite side. This would simply change the direction of movement of the segment when lifting the blade.

As another modification, if desired, the hand-wheels N could be disposed to stand crosswise of the turn-table G, or at right angles to the plane of the gear-segments M. The pinion

and segment gears in that case would be made as bevels, instead of spur-gearing. I prefer, however, the relative arrangement shown.

The hand-wheel, gear-segment, and pinion mechanism operating as set forth may be employed for manipulating the blade or scraper devices in a road-machine of other construction than the one herein illustrated with beneficial results, and I include such use as within the scope of my invention.

Attached to the blade D, which is hinged at d' for backward and forward pitch or tipping action, is a lever, R, the moving end of which extends to a position within reach of the operator, and which enables him to vary the forward and backward inclination of the blade D, and a recessed rack or segment, R', or other suitable device is combined therewith in a manner to retain said lever, together with the scraper-blade, at different degrees of pitch adjustment. The rack or locking bar R' is in the present instance arranged through a seat in the lever R to serve as a guide therefor, and it is pivoted to the swinging frame G in a manner to permit its series of recesses or lugs to catch onto a bolt or lug in said lever R. The rear end, r, of the locking-bar R' is in position to be depressed by the foot of the operator when he desires to release the lever R for changing the adjustment, which is done by raising the bar out of engagement with the interlocking lug, and rocking or pitching the scraper or blade forward or back by means of said lever R. The end of the lever R which connects with the blade D may be attached with a holding bolt and loop, as indicated, so that either end of the blade D can be raised without imparting a sidewise movement to the lever.

T indicates an upright shaft supported in suitable bearings at the rear of the push-frame C, having at its upper end a handle or wheel, T', for turning it, and provided below with a sprocket wheel or sheave, T², for engaging the links of a chain, V, which passes around said wheel T², and has its ends respectively connected with the blade or reversible parts of the scraper mechanism, so that revolution of the hand-wheel T' by the operator will draw upon the chain and swing the scraper-blade D horizontally to different positions of adjustment, accordingly as the wheel is turned to the right or left. The ends of the chain V may be attached directly to the blade D or to the hinge-pieces d', or to the push-bars F, suspending-bars, or the swinging frame, as such parts move with the blade, and draft on the chain will effect the oblique adjustment of the scraper mechanism. Said chain may pass to the wheel T² either above or below the bars of the thrust-frame.

The operation of my improved machine for making road is as follows: The machine is drawn over the road or ground to be worked by horses or cattle attached thereto in the ordinary manner. The driver occupies the seat X, and the attendant stands upon the plat-

form A'. For raising or depressing the end of the blade, the attendant takes hold of the rim of the hand-wheel N, places his foot upon the brake or stop pedal P, and as the stop is relieved from the rim he gives the wheel a turn in proper direction and to the required extent, and this movement being transmitted by the gearing to the bar H effects the desired adjustment of the blade up or down, accordingly as the wheel is revolved toward the right or left. To horizontally reverse or change the diagonal adjustment of the scraper, the attendant places his foot upon the pedal K, the depression of which releases the push-bars from their locking devices. Then by revolving the hand-wheel T' the scraper is swung to the desired position. The swing-frame G and mechanism for vertically adjusting the scraper also swing to the new position in unison with the scraper-blade, so that the pitch-lever R and the hand-wheels and elevating mechanism bear the same relation to the scraper-blade at all positions of its adjustment.

In lieu of making the push-bar lock with a dog that swings up or down from the bar F, the locking parts may be arranged so as to have the push-bar itself moved to and from the catch-dog, or so that the lugs will clutch with that portion of the axle on which the strain is borne. This can be effected by a dropping and lifting guide for supporting said bar F, the same being actuated by a crank or lever connection under control of the attendant.

The adjustable push-bars F and their detachable fastening devices may be used with beneficial result in road-machines wherein the blade-lifting mechanism is of other construction than that herein illustrated, and I desire to include such use within the scope of my invention.

The push-bars, turn-table, adjusting gear, and suspending mechanism, arranged as herein shown and described, may be employed with a scraper-bar carrying a series of points or scarifiers as well as with a smooth-edged scraper-blade.

I am aware that a road-machine has heretofore been patented (see Patent No. 160,535) in which a V-shaped thrust-frame, a turn-table, and a diagonally-reversible scraper are employed, and I do not therefore herein make claim to such features, except as combined with other devices which I have applied in connection therewith.

I have in a separate application for Letters Patent (see Serial No. 164,547,) described a system of non-adjustable push-bars as adapted for use in a "stiff-angled" or non-reversible road-machine. Therefore it will be understood that my present claims contemplate the adjustment of the push-bars or their adaptation for machines in which the scraper-bar is capable of diagonal adjustment or reversal for use in either right or left oblique position in relation to the direction of draft.

What I claim as of my invention, and desire to secure by Letters Patent, is—

1. In a road-machine, the combination, substantially as hereinbefore described, with a diagonally-reversible scraper bar or blade, of adjustable push-bars adapted for sustaining the ends of said scraper from the rear and permitting adjustment thereof to either right or left oblique position.
2. The combination, substantially as hereinbefore described, of a diagonally-adjustable scraper suspended beneath a carriage-frame mounted on front and rear axles and wheels, adjustable push-bars extending from the ends of said blade to the rear of the carriage, and means for adjustably fastening said push-bars at their junction with the carriage.
3. In a road-machine, the combination, substantially as hereinbefore described, of a carrying-frame mounted on front and rear wheels, a thrust-frame in rear of the scraper, a diagonally-reversible scraper centrally pivoted at the front of said thrust-frame, and adjustable push-bars connected at their front ends with the respective ends of said scraper and detachably connected at their rear to the carriage or axle of the machine, for the purpose set forth.
4. In a road-machine, the combination, substantially as described, with a carrying-frame mounted on front and rear wheels, a vertically-swinging V-shaped thrust-frame hinged upon the rear axle, and a horizontally-adjustable scraper pivoted on said thrust-frame and suspended from adjusting mechanism mounted on the carriage, of longitudinally-adjustable push-bars hinged to the respective arms of said scraper, and locking devices detachably connecting said push-bars with the rear part of the machine, for the purposes set forth.
5. In a road-machine, the combination, substantially as described, of a diagonally-adjustable scraper bar or blade, adjustable push-bars sustaining the respective ends of said scraper from the rear, locking devices detachably engaging said push-bars at the several positions of their adjustment, and disengaging levers or means for releasing said push-bars in convenient reach of the operator from his position on the platform of the machine.
6. In a road-machine, the combination, substantially as described, of a diagonally-reversible scraper-blade suspended beneath a carriage or body frame mounted on wheels, adjustable push-bars sustaining the respective ends of said scraper from the rear, locking-dogs engaging and detachably securing said push-bars at their junction with the carriage or axle, actuating-levers connected with said dogs, and the foot-pedal connected with said levers, for the purpose set forth.
7. In a road-machine, the combination of the carrying-frame, the V-shaped thrust-frame, the diagonally-reversible scraper pivotally attached thereto, the adjustable push-bars hinged to the ends of said scraper and provided with recesses to receive engaging-lugs, the rear axle, consisting of a round shaft to which the thrust-frame is hinged, and devices for attaching and detaching said push-bars therewith under control of the operator, as set forth.
8. In a road-machine, the combination, substantially as described, of a carriage-frame mounted on wheels, a swinging frame or turn-table mounted on said carriage, a diagonally-reversible scraper suspended from lifting and adjusting mechanism mounted upon said swinging frame, a central thrust-frame pivotally connected at its front end with said scraper and hinged at its rear to the carriage-axle, and side push-bars hinged to the ends of said scraper and detachably connected with the carriage-axle by fastening devices under control of the operator, for the purposes set forth.
9. In a road-machine, the combination, substantially as described, with a diagonally-adjustable scraper and the scraper-supporting bars, of the pinion, the segment-gear connected with said pinion, and the hand-wheel and pinion, for the purpose set forth.
10. In a road-machine, the combination, substantially as described, with a carriage-frame mounted on wheels, of a swinging frame centrally pivoted thereon, a vertically-adjustable V-shaped thrust-frame, the diagonally-reversible scraper pivotally connected to the front end thereof, adjusting suspending-bars connecting the ends of the scraper with lifting-gears supported on the respective arms of the swing-frame, and the gear-segments, pinions, hand-wheels, and brake mechanism mounted on said swing-frame in respective right and left order for independently adjusting the ends of said scraper, as set forth.
11. In a road-machine, the combination, substantially as described, with a diagonally and vertically adjustable scraper-blade having rack-bars connected for effecting adjustment at the respective ends of said scraper, a pinion (or pinions) engaging and working said rack-bars, and the scraper, of a gear-segment fixed to and working said pinion, a second wheel or pinion engaging said gear-segment, and a hand-wheel fixed to said second pinion for imparting motion to said mechanism for adjusting the scraper, as set forth.
12. In a road-machine, the combination, with an adjustable scraper-blade provided with a hand-wheel (or hand-wheels) for operating the blade-adjusting devices thereof, of a stop device that engages with said wheel for retaining the wheel and scraper at position of adjustment, substantially as set forth.
13. In a road-machine, the combination, substantially as hereinbefore described, of a diagonally-adjustable scraper-blade pivoted to a vertically-adjustable push-frame, an upright shaft supported on said frame and provided with a sprocket wheel or sheave, and a chain passing around said wheel or sheave and connected at its ends with the respective arms of the blade, and a hand device for operating said shaft from the platform of the carriage, for the purpose set forth.
14. In a road-machine, the combination,

substantially as described, of a V-shaped thrust-frame sustaining the blade from the rear of the machine, a diagonally-reversible scraper-blade pivotally connected to said frame, a hand-shaft and sprocket-wheel supported in connection with said frame, and a chain engaging said sprocket-wheel and having its ends connected with the blade, respectively at the right and left of its pivoted center, for the purpose set forth.

15 15. In a road-machine, the combination, substantially as described, of a carriage-frame, a diagonally-reversible scraper-blade, rearwardly-extending longitudinally-adjustable push-bars connected with the ends of said blade, a hand-shaft and sprocket-wheel, a shifting-chain engaging said sprocket and having its ends connected with the respective ends of the blade, and devices for detachably fastening the mechanism with the blade at different positions of diagonal adjustment.

20 16. In a road-machine, the combination, substantially as described, of the carrying-frame mounted on front and rear wheels, the swing-frame pivoted on said carriage for right and left diagonal adjustment, a scraper suspended from the arms or ends of said swing-frame by racks and gears, and hand-wheels for imparting motion thereto for raising and 25 lowering the end or ends of the scraper, and brakes or stop devices adapted to be operated by the foot engaging with said wheels, substantially as set forth.

30 17. In a road-machine, the combination, substantially as hereinbefore described, of the carriage, the turn-table or swing-frame, a diagonally-adjustable scraper-blade suspended therefrom, and a lever for controlling the pitch adjustment of said blade.

35 18. In a road-machine, the combination, substantially as described, of the carrying-

frame mounted on front and rear wheels, the swing-frame supported thereon for right and left diagonal adjustment, the scraper-blade suspended therefrom and hinged for backward 45 and forward tipping action, a thrust-frame sustaining the blade from its rear, and a lever and locking device connected with the swinging parts for adjusting the pitch of said blade, as set forth.

50 19. The combination, substantially as described, with the scraper-blade adapted to have independent vertical adjustment at either end and hinged for forward and backward pitch adjustment, of a pitch-adjusting lever 55 attached to said blade by a pivot adapted to permit such vertical adjustment without imparting sidewise action to the pitch-adjusting lever, as set forth.

20. In a road-machine, the combination, substantially as described, of the adjustable scraper-blade D, the longitudinally-adjustable push-bars F, and guides e, adapted to sustain the rear part of said push-bars, as set forth.

25 21. The combination, substantially as described, with the swing-frame G and hand-wheels N, of brake mechanism P, arranged on said frame for operation as set forth.

30 22. In a road-machine, having a diagonally and vertically adjustable scraper, the combination, with mechanism by which the scraper is suspended or adjusted, of a hand wheel and pinion, N N', gear segment and pinion M L, and a rack, as h', meshing together for action as set forth.

35 Witness my hand this 26th day of May, A. D. 1885.

GEORGE W. TAFT.
